CONCRETE WALL BUILDING BLOCK

Enoch B. Johnson and Arnold A. Kaehler,
Red Wing, Minn.

Application August 31, 1942, Serial No. 456,758

1. Claim. (Cl. 72—43)

This invention relates to hollow building blocks having the outer and inner wall sections thereof constructed of molded concrete, and particularly to blocks of that type which when properly laid and in use will substantially prevent seepage of moisture from the outside of a building to the inside wall which is so common in concrete block constructions.

It is an object of our invention to provide simple, inexpensive building block constructions which substantially eliminate seepage of moisture and the formation of frost on the inner wall, and which are so constructed as to permit slight give or flexibility between inner and outer concrete walls formed therefrom, which may be easily laid and more readily handled and filled with insulating material than most concrete blocks now extensively utilized, and which further are adapted for installation or attachment of rafters, joists and window frames.

A more specific object is the provision of building block constructions wherein inner and outer wall sections or slabs of molded concrete are utilized, spaced apart and connected together with some degree of flexibility by bridge members constructed of wood or other relatively moisture and heat repellent and fibrous material, with such bridge members related to constitute handling means for facilitating laying of the blocks as well as means for nailing or otherwise securing rafters, joists, window frames and other structures.

A further object is the provision of building structure of the class described wherein the outer and inner walls formed by such units may be made of different materials, and whereby the bridging members are so related with the heights and lengths of the concrete wall sections or slabs as to facilitate laying of the units, filling of the hollow wall with insulating material and non-interference with parts of successive units when the wall is formed.

Still another object is the provision of building blocks of the class described wherein not only the wall sections proper but the corners of a building constructed from such units will have its inner and outer wall sections spaced apart and connected by bridging members repellent to moisture and heat.

These and other objects and advantages of the invention will more fully appear from the following description made in connection with the accompanying drawing, wherein like reference characters refer to the same parts throughout the views, and, in which:

Fig. 1 is an isometrical view illustrating a portion of a corner of a building constructed from our improved blocks;

Fig. 2 is a top plan view, some portions broken away, of one of our standard building units;

Fig. 3 is a front elevation of the same with a part of the block broken away and shown in vertical section;

Fig. 4 is a plan view of a portion of one of the walls broken away illustrating a corner block structure;

Fig. 5 is a rear elevation of the same with a portion thereof shown in vertical section;

Fig. 6 is a top plan view of a half block used in conjunction with window or door frames and corners, and

Fig. 7 is a vertical section taken on the line 7—7 of Fig. 6.

Our building construction includes for a building or pair of adjoining walls a multiplicity of standard wall blocks and a requisite number of special corner blocks cooperating therewith to produce a hollow wall wherein the inner section is maintained free from transmission or seepage of moisture and frost.

The standard full sized wall units comprise inner and outer relatively thick slabs 11 and 12 respectively which preferably are constructed of molded concrete or other material bonded together by a suitable cement. The inner wall section or slab 11 may be constructed of finer or

very different filler material than the outer to suit various needs. These two slabs 11 and 12 are connected together and spaced apart by means of two or more bridging members 13 which have their ends 13a embedded in the material of the slabs preferably installed during the molding of the block by a suitable concrete block or tile machine. The bridging members 13 are preferably constructed of wood or other fibrous material or composition which is repellent to moisture and heat. The height of these bridging members is considerably less than the height of the slabs 11 and 12 so that the upper and lower edges of members 13 may be disposed some distance inwardly of the corresponding edges of the slabs. Bridging members are also disposed some distance inwardly of the ends of the block formed as clearly shown in Fig. 3. The embedded ends 13a of the bridging members are provided with

suitable anchoring means which may be of any desirable form and which, as shown, constitute dovetails processed in the ends of the members for securely connecting the slabs together. The bridging members are preferably of suitable height so that they may be grasped for conven-

50
55

iently handling the block or laying the blocks to form a wall. The blocks described are laid in the manner of standard concrete blocks now extensively utilized with suitable cement bonding successive layers of the block together and being interposed between the opposing ends of successive blocks in the several layers.

To form the corner joint between adjoining angularly disposed walls we provide a somewhat different corner block construction illustrated particularly in Figs. 4 and 5. Here in the molding of the block the outer wall 14 is provided with an integrally molded perpendicular end section 14a extending rearwardly to the inner surface of the inner slab 15. The bridging member 13 constructed of wood or other fibrous material and identical with the bridging members first described with reference to the standard wall block, connects the opposing ends of the slabs 14 and 15 and has the anchoring means such as the dovetailed extremities 13a embedded in the material of the two slabs. Slab 15 is connected to the end section 14a of the block through the medium of an insulating bridging or connection member 16 which may be in the form of a 2 x 4 or other bar of suitable fibrous material having flexibility and some resiliency but being comparatively repellent to moisture and heat. The bar 16 is embedded in the concrete material of the block during the molding of the same with one of its plane faces disposed flush with the inner wall of the block and with preferably its parallel face disposed a short distance inwardly of the outer face of the inner slab 15. A second plate or other strip 16a, as shown, is secured to the 2 x 4, 16 with its outer face disposed flush with the outer face of the slab 15 of the block. The bar 16 is securely anchored and embedded in the concrete or other plastic material by suitable means such as a series of spaced anchoring pins or nails 17 extending outwardly from the vertical sides of the bars 16. It will, of course, be understood that members 16 and 16a may be integrally constructed by rabbeting the longitudinal edges of a bar of suitable material.

In laying the walls of a building made from our improved units the blocks are conveniently grasped and handled through the medium of the bridging members 13 and are laid and cemented together in staggered successive layers, as shown in the drawing. In forming the corners to adjoining walls our improved corner blocks are used, it being essential that in each instance the corner block is laid with the bridging bar 16 disposed on the inner side of the block and opposing the end of the standard wall block at the other side of the corner formed. Thus in Fig. 1 in laying the next layer of blocks the next corner block will be reversed from its position shown in the uppermost layer of blocks or, in other words, turned upside down from its position in Fig. 1 with the moisture repelling bar opposing the end of the adjacent standard wall block on the right-hand wall.

With our improved construction it will be seen that the individual blocks are easily handled through the medium of the relatively narrow bridging members 13, are of considerably less weight than the concrete block now in wide use which utilize molded concrete bridging or end members to connect the inner and outer slabs, and because of the flexibility and resiliency of the bridging members make possible for a small amount of shifting between the outer and inner

sections of the walls formed by means of the inner and outer slabs.

It will further be apparent that no parts of the walls formed are connected between the inner and outer sections or slabs through the medium of concrete or other relatively porous plastic materials. The inner and outer slabs of the standard wall units are connected only through the medium of the bridging members 13 which are repellent to moisture, and the moisture repellent bars 16 prevent transmission of moisture from the outer slabs 14 to the inner slabs 15 of the corner blocks as well as transmission of moisture in the abutting standard wall block between the connected ends of the slabs 11 and 12. It will further be apparent from our improved structure that the wooden or other fibrous bridging members and bars 16 enable joists, rafters, and window frames to be readily attached by nails or screws which is an additional advantage over the conventional types of concrete blocks now in wide use.

In Figs. 6 and 7 we disclose a half block which may be used where window frames or door frames are required in a wall and also in conjunction with formation of joints or corners between two adjoining walls. This half block comprises inner and outer slabs 18 and 19 respectively constructed of molded concrete or other molded plastic material and connected together and spaced apart, one end of the block being formed by means of a bridging member 13 similar to the bridging members previously described having the anchoring dovetails or other means at the embedded ends thereof. Bridging member 13 is disposed inwardly of the extremities of the block and also inwardly of the upper and lower edges of the slabs 18 and 19. The other ends of slabs 18 and 19 are connected together and spaced apart by a bar 20 with a plate 20a of less width attached thereto, said bar and plate being similar to bar 16 and the related plate 16a used in the corner block construction. Bar 20 has its outer side flush with the adjacent side walls and extends the full height of the block. The bar is constructed of wood or other fibrous moisture and heat repellent material and is embedded in the concrete in the molding of the block and has retaining nails or other anchoring means extending from the longitudinal edges thereof into the concrete.

If a half block is needed in the construction of a wall with a window frame, door frame, or other opening therein, it may be laid with the wooden bar 20 disposed towards the frame for prevention of moisture seepage and heat transmission between the slabs and also for facilitating attachment of the window or door frame to the wall. It may also be used in conjunction with the corner formed by two adjoining walls with the bar 20 disposed flush against the bar 16 of a corner block, or, in some instances, with bar 20 disposed in opposition to the end of an adjoining standard wall block.

It will, of course, be understood that various changes may be made in the form, details, arrangement and proportions of the various parts without departing from the scope of our invention.

What is claimed is:

A corner building block for the construction of walls comprising an outer molded slab having its main section provided with inner and outer parallel flat surfaces and having an end section integrally formed therewith and extending at a

right angle thereto, a second molded slab of less length than said first slab and spaced from the main portion thereof having parallel flat surfaces, a transverse handling and connecting member constructed of tough, fibrous material interposed between the ends of said slabs adjacent one end of the block and having its ends embedded and anchored in said slabs, and a second connecting member also constructed of tough, fibrous material such as wood interposed between the end sec- 10

tion of said first slab and the opposing end of said shorter slab and extending the full height of said slabs, means for anchoring the ends of said second connecting member within the connected portions of said slabs, said second connecting member having its outer surface disposed substantially flush with the outer surface of said shorter slab.
